Chas. A. Klinkner,
By his Atty., Bornet & Brown

UNITED STATES PATENT OFFICE.

CHARLES A. KLINKNER, OF SAN FRANCISCO, CALIFORNIA.

COMBINED INKING-PAD CASE AND STAMP-RACK.

SPECIFICATION forming part of Letters Patent No. 236,166, dated January 4, 1881.

Application filed October 2, 1880. (No model.)

To all whom it may concern:

Be it known that I, CHARLES A. KLINKNER, of the city and county of San Francisco, in the State of California, have made and invented a new and useful Improved Inking-Pad Case and Stamp-Rack for Hand Printing-
5 Stamps; and I do hereby declare that the following is a full, clear, and exact description of the same, reference being had to the accompanying drawings.

This invention consists, first, in a reversible inking-pad frame of peculiar construction; and, secondly, in the combination of said inking-pad frame and an inclosing-casing provided with a stamp-rack on its upper surface, as hereinafter described, and pointed out in the claims.

In the said drawings, Figure 1 shows a perspective view of my pad-holder and stamp-rack. Fig. 2 shows the pad-holder removed from the base. Fig. 3 is a front elevation of the base and its stamp-rack.

I make the case A so that it can be secured in place upon a counter, desk, or other place 25 to form the bottom B. The front and rear sides of this case are open, but the ends are closed, and lugs c are provided on these ends as a means for fixing it in place.

The opening d in the case is to receive 30 a pad-frame, E, which slides into and out from the case, after the manner of a drawer. This frame E receives and holds two pads or inking-surfaces, f, one of which is shown on the top in Figs. 1 and 2, the other one being 35 underneath. These two pads permit different-colored inks to be used.

The rim of the pad-frame E is made wide enough to form a projecting edge all around the pad, or else lugs or projections g' g' are 40 provided at the corners, so as to keep the inking-surface clear of the platform B beneath it, and of the top of the case A above, when the pad is drawn out of and returned to the case A. This pad E slides in and out horizontally, 45 after the manner of a drawer, and is kept from being drawn entirely out of place by the action of two depending lugs, g g, upon the under side of the case A, so placed as to be in line with and form stops for the rim or projecting part g' of the pad-frame E.

The pad-frame is introduced into and re-

moved from the protecting-case A by simply raising up the front of the frame toward a vertical position high enough to disengage the rear edge, g', and allow it to slip past the 55 lugs g, but while working in a horizontal position the frame E is connected with the case and prevented from being entirely drawn out therefrom by these stops g.

Upon the top of the case A, I fix the upright 60 stamp-support H, consisting of the post H', having upon it the radiating arms, between which are provided suitable slots, recesses, or other retaining-places to receive the handles and support the stamps around the post H'. 65 This provides a convenient support for a number of hand-stamps, which by this means are always kept at hand and convenient to the inking-pad.

This case and rack can be made of any size 70 to accommodate and be used with a greater or less number of stamps, and it can be made of other shape than the rectangular form shown in the drawings.

As thus constructed I combine in one article a pad-case and holder and a convenient rest or rack for the hand-stamps, which is adapted for general use in banks, mercantile houses, and like places where a number of printing and canceling stamps are in use. 75

Having thus fully described my invention, what I claim, and desire to secure by Letters Patent, is—

1. A reversible inking-pad frame, E, having projecting rim or lugs on both its top and 85 bottom, and provided with inking-pads on its upper and under sides, substantially as set forth.

2. A combined inking-pad case and stamp-rack for hand-stamps, consisting of the casing A, having rack H, and the detachable and reversible sliding frame E, with inking-pads on its top and bottom and projecting rim or lugs on both top and bottom edges, as and for the purposes described. 90

In witness whereof I have hereunto set my hand and seal.

CHARLES ALEXANDER KLINKNER. [L. s.]
